EDWARD W. HILL, OF CHICAGO, ILLINOIS, ASSIGNOR TO A. B. DICK COMPANY, OF CHICAGO, ILLINOIS, A CORPORATION OF ILLINOIS.

METHOD OF AND APPARATUS FOR PREPARING STENCIL-SHEETS FOR DUPLICATING.

1,188,937.

Specification of Letters Patent. Patented June 27, 1916.

Application filed September 18, 1915. Serial No. 51,324.

To all whom it may concern:

Be it known that I, EDWARD W. HILL, a citizen of the United States, residing at Chicago, in the county of Cook and State 5 of Illinois, have invented certain new and useful Improvements in Methods of and Apparatus for Preparing Stencil-Sheets for Duplicating, of which the following is a specification.

10 The invention concerns particularly the process of stencil-duplication now in common use, in which is employed a stencil-sheet of open porous material coated with a compound consisting largely of coagulated protein. Such stencil-sheets are normally dry but hygroscopic and before being stencilized are softened by the application of moisture thereto. In what is known as the "dermatype process," such a stencil-sheet 15 is combined with a backing of relatively hard impervious material, bearing upon the surface next adjacent to the under side of the stencil-sheet a sheet of absorbent material to which, the stencil-sheet having 20 been lifted, the moisture is applied, after which the stencil-sheet is pressed into contact with such material to transmit the moisture to such sheet. The type or other characters are then formed, by pressure, in 25 the stencil-sheet, after which such sheet may be placed in a duplicating-machine and multiple copies made by passing ink through the interstices therein. This process is used very largely for typewriter stencil-duplication; also for autographic work, 30 for architectural and engineering drawings and the like. In many cases, drawings are made upon the stencil-sheet and thereafter the same sheet is typed in a writing-machine, as, for example, to add descriptive 35 notes to the drawing. In the copying of a drawing upon such a stencil-sheet, an approved method involves placing the stencil-sheet, a suitable backing and the drawing 40 to be copied upon a glass plate, an electric lamp being placed below the same, so as to project the lines of the copy through the backing and, to some extent, through the stencil-sheet, permitting such lines to be followed 45 upon the latter by means of a suitable stylus, whereby passages are opened in the stencil-sheet for the subsequent transmission of ink in the production of multiple 50 copies.

55 In the utilization of the process above referred to for certain purposes, notably the duplication of drawings and similar work, difficulty has been experienced not only in applying the moisture evenly to the stencil-sheet but also in retaining the moisture, so as to maintain the stencil-sheet in 60 proper condition for stencilization, through an extended period of time. A single application of moisture to the stencil-sheet, while sufficient for a short time, is apt to result in the drying out of the sheet before the 65 operation of stencilizing has been completed. Successive applications of moisture are not only annoying and time-consuming but are also apt to result in lack of uniformity in the finished work. Again, where the 70 preparation of the drawing itself consumes considerable time and yet after the drawing has been completed descriptive matter must be typed upon the stencil-sheet, this 75 involves additional application of moisture before the sheet is placed in the writing-machine and with the same result, *i. e.*, lack of uniformity. These and other difficulties 80 hereinafter pointed out are overcome under the present invention, in which, in conjunction preferably with a "composite" stencil-sheet consisting of the stencil-sheet proper and a suitable backing secured thereto, I 85 employ a thin, flexible and preferably transparent sheet of a suitable material such as celluloid, such sheet being placed between the stencil-sheet and the backing and having its upper surface, or both upper and lower 90 surfaces, roughened, as, for instance, by pressing the same against sand-blasted metal or glass. The moisture, instead of being applied to the backing-sheet or to an absorbent sheet laid thereon, is applied to 95 the upper surface of the celluloid sheet and the stencil-sheet pressed down in contact therewith and smoothed out, so that there shall be a uniform application of moisture throughout the area of the stencil-sheet to 100 soften the material thereon preliminarily to the stencilizing operation. The minute depressions in the upper surface of the celluloid sheet serve primarily to hold a sufficient quantity of the moistening fluid to maintain the stencil-sheet in usable condition 105 throughout an extended period of time, and secondarily to maintain the sheet flat and resist the tendency thereof during a prolonged operation thereon to become wrinkled or distorted. The celluloid sheet may, if 110

desired, advantageously be roughened upon both sides, not only to avoid placing the wrong side next adjacent to the under side of the stencil-sheet (as might inadvertently be done were but one side roughened), but also to prevent the tendency of such sheet, during the stencilizing process, to creep or become displaced upon the underlying back-ing-sheet or the absorbent sheet combined therewith.

The invention is illustrated in the accompanying drawing, in which—

Figure 1 is a plan view and Fig. 2 a perspective view, illustrating a "composite" 15 stencil-sheet provided with the roughened intermediate plate or sheet hereinabove described.

In these drawings, the stencil-sheet proper, 1, is shown as attached at its forward edge, 20 2, as by a suitable adhesive, to the attachment edge 3 of the backing-sheet 4. Such backing-sheet may be of ordinary, fairly stiff paper, or the upper surface thereof may, if desired, be provided with an attached absorbent surface, such as is described in Letters Patent No. 1,101,259, granted June 23rd, 1914. Between the stencil-sheet 1 and the backing-sheet 4 is interposed the sheet 5, 25 preferably of thin, light, transparent and flexible material, such as celluloid, and provided on either the upper surface or on both upper and lower surfaces with a roughened exterior formed by suitable means, such as that hereinabove specified. Celluloid possesses the desired characteristics and is capable, in addition, of maintaining its roughened exterior, and may, therefore, be advantageously employed in practising the process herein disclosed. The characteristics 30 of lightness, thinness and flexibility are desirable from the standpoint of convenience in use. The characteristic of transparency is particularly availed of where, as hereinabove indicated, it is desired to trace maps, 35 drawings, etc., upon a stencil-sheet by means of a copy placed below the same, the lines upon such copy being projected by a suitable lamp. In this process, the transparent roughened sheet offers no obstacle to the necessary projection of the lines to be copied.

While I prefer to roughen the entire upper surface or the entire areas of both upper and lower surfaces of the celluloid sheet, it should be understood that this is not essential save where the overlying stencil-sheet is to be stencilized. In other words, the celluloid sheet may, if desired, be provided with unroughened margins, coextensive with the margins of the stencil-sheet not to 55 be utilized for the formation of stencil interstices therein. I consider it important, however, that the roughening of the celluloid sheet be not a coarse roughening but of very considerable fineness (such as results from the roughening means above de-

scribed), for while, under my invention, it is the purpose that the minute depressions shall hold a sufficient quantity of the moistening fluid to maintain the stencil-sheet in usable condition throughout an extended period of time, it is also desirable that during the stencilizing process the point of the stylus (used for autographic work or for ruling, drawing or sketching) shall pass easily and smoothly over the surface of the stencil-sheet, practically unaffected by the minute roughness of the underlying celluloid sheet.

The use of thin and flexible material, such as celluloid, for the interposed sheet or plate is desirable, since it may not easily be broken, does not require too great separation of the stencil-sheet and backing, and may be held immovable, at one point, relatively to the underlying backing and copy 85 and yet raised at another point either for direct inspection of such copy or to adjust the position of the copy relatively to the stencil-sheet, backing and interposed sheet or plate.

In addition to the advantages hereinbefore pointed out as arising from the invention under disclosure, a further advantage is realized in that by the use of the intermediate celluloid sheet the premature moistening, and consequent softening, of the absorbent sheet commonly associated with the backing-sheet is avoided, in one important department of stencil work. Where, for example, a drawing is to be formed upon the 100 stencil-sheet, the procedure is as above indicated, the celluloid sheet being laid upon the absorbent backing and the moisture applied thereto for transmission to the stencil-sheet. If, now, it be desired to add to the 105 drawing depicted upon the stencil-sheet descriptive memoranda, either autographically or by means of a writing-machine, this may be done either without further moistening or the celluloid sheet may be removed and the moistening fluid applied to the absorbent backing, after which, the stencil-sheet being pressed into contact with such backing so as to renew the application of moisture to such sheet, the additional memoranda may be placed upon the stencil-sheet in any desired manner, such, for instance, as by the use of a stylus or by placing the composite sheet in a writing-machine and typing thereon.

Having now described my invention, what I claim as new therein and desire to secure by Letters Patent is as follows:

1. The method of preparing a stencil-sheet for duplicating, which involves applying moisture to the roughened surface of a sheet of thin, hard material, superimposing a stencil-sheet upon said surface, and then stencilizing said stencil-sheet by pressure, substantially as set forth.

2. The method of preparing a stencil-sheet for duplicating, which involves applying moisture to the roughened surface of a sheet of thin, hard flexible material, superimposing a stencil-sheet upon said surface, and then stencilizing said stencil-sheet by pressure, substantially as set forth. 30
3. The method of preparing a stencil-sheet for duplicating, which involves applying moisture to the roughened surface of a sheet of thin, hard, transparent material, superimposing a stencil-sheet upon said surface, and then stencilizing said stencil-sheet by pressure, substantially as set forth. 35
4. The method of preparing a stencil-sheet for duplicating, which involves applying moisture to the roughened surface of a sheet of thin, hard, flexible, transparent material, superimposing a stencil-sheet upon said surface, and then stencilizing said stencil-sheet by pressure, substantially as set forth. 40
5. The method of preparing a stencil-sheet for duplicating, which involves applying moisture to the minutely roughened surface of a thin sheet of flexible non-absorbent hard material, superimposing a stencil-sheet upon said surface, and then stencilizing said stencil-sheet by forming desired characters thereon under application of pressure, substantially as set forth. 45
6. In stencil-duplication, the combination with a sheet of thin, hard, flexible, non-absorbent material having minute depressions formed on and closely arranged over its upper surface, adapted to receive moisture, of a stencil-sheet superimposed thereon, said depressions being sufficiently minute so that a stylus point may pass easily and smoothly over the surface of the stencil-sheet, substantially as set forth. 50
7. In stencil-duplication, the combination with a sheet of hard, transparent material having a roughened surface, of a stencil-sheet superimposed upon said surface, substantially as set forth. 55
8. In stencil-duplication, the combination with a sheet of thin, hard, flexible, transparent material having a roughened surface, of a stencil-sheet superimposed upon said surface, substantially as set forth. 60

This specification signed and witnessed this 15th day of September, 1915.

EDWARD W. HILL.
